(57) **CLAIM**

The ornamental design for a tray cover, as shown and described.

DESCRIPTION

FIG. 1 is a top perspective view of the tray cover;

FIG. 2 is a top plan view of the tray cover shown in FIG. 1;

FIG. 3 is a bottom plan view of the tray cover shown in FIG. 1;

FIG. 4 is a front elevational view of the tray cover shown in FIG. 1;

FIG. 5 is a rear elevational view of the tray cover shown in FIG. 1;

FIG. 6 is a right side elevational view of the tray cover shown in FIG. 1;

FIG. 7 is a left side elevational view of the tray cover shown in FIG. 1;

FIG. 8 is another perspective view of the tray cover shown in FIG. 1 showing the tray cover when used to cover a tray;

FIG. 9 is a bottom perspective view of the tray cover shown in FIG. 8; and,

FIG. 10 is another perspective view of the tray cover shown in FIG. 1 showing the tray cover when used to cover a tray and the tray is connected to an infant high chair.

The broken lines in the drawings show portions of the tray cover or environmental features which form no part of the claimed design.
